UNITED STATES PATENT OFFICE.

MORRIS LOWY, OF NEW YORK, N. Y.

FOLDING COT.

1,246,123.

Specification of Letters Patent. Patented Nov. 13, 1917.

Original application filed August 13, 1915, Serial No. 45,334. Divided and this application filed August 25, 1916. Serial No. 116,852.

To all whom it may concern:

Be it known that I, MORRIS LOWY, a citizen of the United States, and a resident of the city of New York, in the county of New York and State of New York, have invented certain new and useful Improvements in Folding Cots, of which the following is a specification.

The present invention relates to folding cots and is divided out of my application for U. S. Letters Patent, filed Aug. 13, 1915, under Serial No. 45,334.

One of the objects of the invention is to simplify the construction of devices of this kind by providing a structure which is light, durable, simple, inexpensive to manufacture, and which can be readily so folded that it will occupy a small space.

Another object of the invention is to produce a folding cot comprising a pair of foldable sections which are united by a short middle section, each of said sections having a pair of legs which are so connected by simple means that by one movement both foldable sections as well as the legs may be folded into a compact upright structure, or opened in readiness for use, and when open the cot will be maintained in its position against premature closure.

With these and other objects in view, which will more fully appear as the nature of the invention is better understood, the same consists in the combination, arrangement, and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

Figure 1 is a perspective view of a cot constructed in accordance with the present invention in its extended position; Fig. 2 is a side elevation of a cot in its folded position; Fig. 3 is a front elevation thereof, also folded; Fig. 4 is a portion of a section taken

on line 4—4 of Fig. 3, on a larger scale; and Fig. 5 is a side elevation of a detail of construction, also on a larger scale.

55

In the drawings the numeral 10 indicates the top frame of the cot. This frame comprises an oblong structure, formed of two similar sections 11 and 12, each of which is constructed, preferably, of angle-irons. The section 11 comprises side rails 13, the outer ends of which are connected by an end rail 14. In a similar manner consists the section 12 of side rails 15, which are connected at their outer ends by an end rail 16. The side rails of both sections of the cot frame are united by a short middle section 17, to which the inner ends of the side rails are pivoted at 18. The middle section comprises two bracket-like structures 19, which are connected by a cross-rod or brace 20, the latter being disposed a substantial distance below the side rails of the frame sections; so as to leave sufficient clearance under the bed bottom to enable the latter 75 to sag under the weight of a person lying thereupon without his body striking or contacting with said cross-rod. Upon the vertical portions of the bracket-like structures 19 are formed lugs 21, to which the side 80 rails of the frame sections are pivoted. The inner ends of the side rails of the frame sections overlap and rest upon these lugs when the cot is in its extended position, the horizontal sections 22 of the brackets then 85 filling the gaps between the inner ends of the horizontal flanges of the side rails.

The top frame carries a bed spring which might serve at the same time as a mattress. For this purpose the said frame is provided 90 with a plurality of apertures 10' in the horizontal flanges of the angle-irons constituting the said frame. Each of these apertures is engaged by one end of a spring 23, the other end of which is attached to a sheet 24 of a 95 suitable fabric or other flexible material. This structure forms a combined mattress and spring, and is adapted to be folded with the cot as the latter is brought into the positions shown in Figs. 2 and 3 of the 100 drawings.

Each of the frame sections 11 and 12 is supported by a pair of legs 25, which are provided with casters 26 for the well-known

purpose. Each pair of legs is braced by a plurality of tie-rods, in the present case by two rods, denoted by the numerals 27 and 28. These rods extend horizontally and 5 transversely of the cot, those denoted by the numeral 27 being disposed near the upper ends of the legs and those indicated at 28 near their lower ends. One pair of legs is pivoted at 29 to the side rails 13, and the 10 other pair at 30 to the side rails 15. The middle section is also supported by a pair of legs, indicated at 31, these legs being fixedly attached to the bracket-like structures 19. Upon the cross-rod or brace 20 15 is mounted a downwardly extending bar 32, having two lugs 32', to which are pivoted at 33 links 34, the other ends of which are fulcrumed at 35 to the tie-rods 28. These links extend in the longitudinal axis of the 20 cot, each of the same connecting one pair of outer legs with the middle legs 31 of the cot. Upon the bar 32 is slidably mounted below the lugs 32' a sleeve 36, which is connected with the links 34. More particu- 25 larly, it is connected with each link 34 by a short link 37, that is pivoted at 38 and 39 to the sleeve 36 and to the link 34, respectively. The purpose of this arrangement will be described hereinafter.

30 The cot is provided with end pieces, that is to say, with a head- and foot-piece, so as to give it the appearance of a normal bedstead. These end pieces are denoted by the numeral 40, and comprise each a bail-shaped 35 frame, the lower ends of which are pivoted at 41 to standards 42, which are carried by the foldable sections of the top frame. A transverse tie-rod 43 connects the vertical portions of each end piece, and to this tie- 40 rod is fixedly attached a lever 44, said lever extending below the respective end rail of the top frame section and being pivoted at 45 to a lever 46, which is oscillatably mounted upon the tie-rod 27 of the respective pair 45 of legs.

The operation of this device is as follows: In order to fold the cot, the operator takes hold of the top frame sections 11 and 12, and moves the central portions of the same 50 upward, swinging them around the pivots 18, which results, due to the connections between the outer legs and the middle legs, in swinging the outer legs around the pivots 29 and 30, until the said legs abut against the 55 respective side rails, and the said side rails are brought into parallel relation to each other into the positions shown in Figs. 2 and 3 of the drawings. At the same time it is to be observed that as the legs 25 are 60 moved into the positions indicated, the levers 44 and 46 shift the end pieces 40 around their pivots 41, until they are brought into substantially parallel relation to the side rails. If desired, an upholstered mattress

and the bed clothing can also be folded with 65 the frame.

As the cot is being folded, the connections between the links 34 and the sleeve 36 will cause the middle section to remain during the folding operation in vertical position, 70 thereby greatly facilitating the folding operation.

The short intermediate section 17 maintains the two folding sections of the cot suitably spaced, to provide a proper place 75 for the legs and links when the structure is folded. Inasmuch as the inner ends of the side rails of the two folding sections rest upon the lugs 21, and the latter are properly supported by the middle legs 31, the said 80 lugs will act as stops when the cot is in its extended position, and thus prevent the cot sections from moving out of alinement under weight. The intermediate section thus not only serves to maintain the two folding sections of the cot suitably spaced, but, by reason of the lugs formed thereon, it acts as 85 a stop to maintain the frame sections in alinement.

In order to keep the cot in its closed position, a catch may be made use of. The catch illustrated in the drawing is made in the form of a leaf-spring 47, which is attached in any suitable manner to the vertical flange of one of the end rails of the top frame, and provided near its outer free end with an aperture 48, in which is adapted to be seated a stud 49, the latter being carried by the end rail of the other section of the top frame. The free end of the spring is curved and extends beyond the respective end rail, when the cot is in its closed position. In folding the cot, the stud will be automatically seated in the aperture of the spring by reason of the free end of the latter being curved. In 100 order to disengage the spring from the stud, the operator steps on the projecting end of the spring, after which the cot can be opened for use.

What I claim is:

1. In a folding cot comprising a pair of foldable cot sections, a short middle section pivotally connected to the inner ends thereof, said foldable cot sections folding transversely of the cot by lifting such inner ends 115 and thereby allowing the outer ends to drop and close toward each other, and a pair of legs pivoted to each of said foldable sections, the combination of a pair of legs attached to said middle section, a downwardly extending bar centrally arranged upon said middle section, and a link connecting the legs of each foldable section with said bar.

2. In a folding cot comprising a pair of foldable cot sections, a short middle section pivotally connected to the inner ends thereof, said foldable cot sections folding transversely of the cot by lifting such inner ends 120 125

and thereby allowing the outer ends to drop and close toward each other, and a pair of legs pivoted to each of said foldable sections, the combination of a pair of legs attached to said middle section, a downwardly extending bar centrally arranged upon said middle section, a link connecting the legs of each foldable section with said bar, and

means for maintaining the legs of said middle section in vertical position during 10 the folding operation.

Signed at New York, in the county of New York, and State of New York, this 23rd day of Aug., A. D. 1916.

MORRIS LOWY.
